US0D1103945S

(12) United States Design Patent (10) Patent No.: US D1,103,945 S
(45) Date of Patent:  *Dec. 2, 2025

(54) HOUSING OF CONTROLLER

(71) Applicant: SONY INTERACTIVE ENTERTAINMENT INC., Tokyo (JP)

(72) Inventor: Daisuke Kurihara, Chiba (JP)

(73) Assignee: SONY INTERACTIVE ENTERTAINMENT INC., Tokyo (JP)

(*) Notice: This patent is subject to a terminal disclaimer.

() Term: 15 Years

(21) Appl. No.: 29/940,971

(22) Filed: May 7, 2024
